UNITED STATES PATENT OFFICE.

JOHN F. McNAMEE, OF INDIANAPOLIS, INDIANA.

DESIGN FOR A CHARM OR PIN.

No. 38,827.

Specification for Design.

Patented Sept. 24, 1907.

Application filed June 15, 1907. Serial No. 379,288. Term of patent 7 years.

To all whom it may concern:

Be it known that I, JOHN F. McNAMEE, a citizen of the United States, residing at Indianapolis, in the county of Marion and State of Indiana, have invented a new, original, and ornamental Design for Charms and Pins, of which the following is a specification, reference being had to the accompanying drawing, forming part thereof.

The figure is an elevation of a charm or pin showing my new design.

I claim:

The ornamental design for a charm or pin, as shown.

JOHN F. McNAMEE.

Witnesses:

AARON E. MARSHALL,
ELIZABETH GRAY.
